UNITED STATES PATENT OFFICE.

EDMUND C. MORGAN, OF NEW YORK, N. Y.; OLIVE EUGENIE MORGAN EXECUTRIX OF
SAID EDMUND C. MORGAN, DECEASED.

METHOD AND APPARATUS FOR MINING COAL.

Application filed February 17, 1923. Serial No. 619,588.

My invention relates to method and apparatus for mining coal embodying a system wherein the coal is mined from the native vein and loaded by extension conveyor mechanism. One of the objects of the invention is the provision of improved apparatus for mining by cutting a plurality of horizontal kerfs in connection with an upright back kerf to effect the cutting of columns of coal to be dislodged and loaded.

A further object of the invention is the provision of improved extensible conveyor mechanism adapted to co-operate with mining mechanism so as to effect the loading of coal simultaneously with the continuance of mining operations.

A further object of the invention is the provision of mining and loading mechanism, particularly adapted for mining coal from the rear end of a pillar in a retreating system by means of which cars may be loaded with coal on a track in a lateral entry with conveyor mechanism that is continuously extended along the rear end of the pillar in accordance with the feeding travel of the mining apparatus.

Another object of the invention is the provision of improved loading apparatus which is adapted to transfer coal from the working face to an entry extending at right angles to such working face for the purpose of loading the coal into cars travelling along such entry.

Another object of the invention is the provision of mine cars particularly adapted for use in connection with extensible conveyor mechanism.

A further object of the invention is the provision of improved winding mechanism for parts of an extensible conveyor.

A still further object of the invention is the provision of mining and loading apparatus adapted to travel and be extended a comparatively long distance along the working face and capable of being retracted and folded into a space having a comparatively short length, thereby adapting the combined apparatus for transportation or adjustment in a limited space in a mine.

A further object of the invention is the provision of means for transferring dislodged coal upgrade, particularly in mines where the vein has a pitch from the horizontal.

Another object of the invention is the pro-

vision of means on mine cars adapted to receive and hold blocks of coal transferred upgrade to such mine cars.

A further object of the invention is the provision of improved haulage mechanism, particularly adapted for shifting an extensible conveyor to a new position in the mine.

A further object of the invention is the provision of means adapted to co-operate with an extensible conveyor for enabling the latter to transfer coal around a corner in a mine and upgrade.

A further object of the invention is the provision of means for mining both coal and foreign material in blocks simultaneously, and loading the coal for transportation from the mine and directing the foreign material into position where it may be left in the mine without interfering with the continued mining and loading operations of the coal from the coal vein.

Another object of the invention is the provision of means for stripping from the floor or roof of a mine chamber, or from both the floor and roof, of layers of coal left by the operation of a mining machine operating along the coal face.

A further object of the invention is the provision of means for stripping horizontal layers, or layers left after mining machine operations have been performed, and loading such stripped coal.

Another object of the invention is the provision of improved framework particularly adapted for mining comparatively thick coal veins by operations with mining mechanism proceeding along terraces or at various elevations.

Another object of the invention is the provision of means for mining comparatively thick coal veins along terraces and conveying the dislodged coal upgrade for loading into a mine car.

Another object of the invention is the provision of improved mining and loading apparatus wherein the mining mechanism cuts the coal along the working face in column form and deposits such coal on conveying mechanism, and wherein the conveying mechanism upon retraction of the mining mechanism transfers the coal into position for loading on to mine cars.

A further object of the invention is the method of mining coal in a retreating sys-

tem, consisting in cutting the coal in column form along the rear end of a pillar, and after the cutting of such coal along the working face conveying it along a path extending from the working face to a lateral entry while the large blocks of the coal remain in alignment with each other along such path extending from the said working face to the said lateral entry, extending at an angle to said working face.

Another object of the invention is the provision of improved flexible loading mechanism comprising a plurality of longitudinally-extending spaced-apart flexible ropes adapted to receive large blocks of coal and be moved therewith on to the bottom of a mine car.

A further object of the invention is an improved method of mining coal which consists in dislodging the coal in blocks and by means of flexible extensible conveyor mechanism loading such coal directly on to the bottom of mine cars and then detaching the conveyor mechanism to leave the said blocks in said mine car.

Another object of the invention is the improved method of simultaneously mining a coal vein and adjacent foreign material and directing the foreign material to a position of non-interference with the loading of the coal and further mining operations.

Another object of the invention is the provision of an improved method of mining coal in a retreating system which consists in simultaneously cutting columns of coal in opposite directions from spaced-apart entries and at the rear ends of intervening pillars, controlling the subsidence of the roof, and providing extensible conveyor systems to mine cars adapted to travel said spaced-apart entries.

A further object of the invention is an improved method of mining coal and foreign material simultaneously which consists in driving a return entry in a retreating system, which return entry is adapted to serve as a ventilating passage and also to permit the mining mechanism to be moved away from the working face and clear the dislodged foreign material when the mining mechanism is retracted to initial position, preparatory to making another cut along the working face.

A further object of the invention is the provision of an improved method for mining coal which consists in driving spaced-apart entries connecting with the working faces extending along the mine vein, mining the coal along such working faces in opposite directions from such entries, and driving an intermediate entry to facilitate ventilation and serving to terminate at such intermediate entry the mining operation extending from the first named entries, whereby the spaced-apart entries may be used for the

mine track and transportation of the mined coal and the intermediate entry may be used both to facilitate ventilation and mining operations.

Another object of the invention is the method of mining coal from comparatively thick veins which consists in providing supporting frame work to enable the mining operations to be started at various elevations and continued in operation along terraces formed in the coal vein itself.

Another object of the invention is the improved method of mining coal from comparatively thick veins by mining the coal longitudinally of the vein at various elevations to provide shelves in the coal vein itself for support during the continued mining operations.

A further object of the invention is an improved method of mining and loading coal from a comparatively thick coal vein by carrying on simultaneously a plurality of mining operations along upright coal faces arranged in terrace formation.

Other objects of the invention will appear hereinafter, the novel features and combinations being pointed out in the claims here-to appended.

In the accompanying drawings, Fig. 1 is a plan view of my improved mining mechanism with a portion of my improved extensible conveyor mechanism attached thereto.

Fig. 2 is a plan view of the remainder of the extensible conveyor mechanism, the right hand end of Fig. 1, when placed in connection with the left hand end of Fig. 2, enables Figs. 1 and 2 to represent in plan the complete mining and loading machine.

Fig. 3 is a side elevation of the construction shown in Fig. 1.

Fig. 4 is a sectional elevation, taken on line 4—4, of Fig. 2, looking in the direction of the arrows; Fig. 4 is also a section taken on the line 4—4 of Fig. 5, looking in the direction of the arrows.

Fig. 5 is a sectional elevation, taken on the line 5—5 of Fig. 2, looking in the direction of the arrows.

Fig. 6 is a transverse sectional view, taken on the line 6—6 of Fig. 3.

Fig. 7 is a transverse sectional elevation of Fig. 3, taken on the line 7—7, looking in the direction of the arrows.

Fig. 8 is a transverse sectional view of the loading mechanism, taken on the line 8—8 of Fig. 3, looking in the direction of the arrows.

Fig. 9 is a diagrammatic view illustrating the provision of a modification which is able to cut three superposed columns of coal along the working face, so that the uppermost column may be shifted to one side and transferred along the space illustrated by the dotted line.

Fig. 10 illustrates diagrammatically an

other modification for cutting the coal in four superposed columns, with provision for shifting the two uppermost columns to one side in superposed relation for transfer 5 along the space illustrated by the dotted line.

Fig. 11 illustrates more or less diagrammatically the modified operating mechanism for the upright kerf cutter, when a plurality of intermediate horizontal kerfs are to 10 be cut to provide more than two superposed columns of coal along the working face.

Fig. 12 is a side elevation of the construction shown in Fig. 11.

Fig. 13 illustrates diagrammatically the 15 arrangement of spaced-apart horizontal kerf cutters at different elevations, so as to prevent such horizontal kerf cutters from cutting bands of foreign material, and thereby retaining such bands of foreign material in 20 the dislodged blocks of coal for better removal after being taken out of the mine.

Fig. 14, on Sheet 3 of the drawings, represents in longitudinal sectional elevation the detachable connection to the forward end 25 of the flexible conveyor belt, as shown at the upper end portion of Fig. 2.

Fig. 15 shows in sectional elevation the type of winding mechanism adapted to be used for the ropes or belts of the loading 30 apparatus.

Fig. 16 is a sectional view showing the manner of retaining a removable reel on the winding drum, illustrated in Fig. 15.

Fig. 17 is an elevational view, partly in 35 section, of the left-hand end of Fig. 15.

Fig. 18 is a sectional elevational view of a portion of the winding mechanism shown in Fig. 15, said view being taken on line 18—18 of Fig. 15, looking in the direction of the 40 arrows.

Fig. 19 is a fragmentary sectional view of a modified reel, particularly adapted for winding simultaneously a plurality of ropes, such as shown in Figs. 1 and 2.

Fig. 20 is a sectional plan view of one of the horizontal kerf cutters of the mining mechanism shown in Fig. 1.

Fig. 21 is a central longitudinal sectional view of Fig. 20 with the addition of the 50 upper portion of the driving motor.

Fig. 22 is an enlarged sectional detail view, taken on the line 22—22 of Fig. 24, looking in the direction of the arrows.

Fig. 23 is a detail sectional view, taken on 55 the line 23—23 of Fig. 24, looking in the direction of the arrows.

Fig. 24 is a plan view of a portion of Fig. 20 and enlarged to show the means for connecting the cutter ring to the circular cutter head.

Fig. 25 is a sectional view of the construction shown in Fig. 24 with the addition of a portion of the construction shown in Fig. 21, including part of the retaining bolt and a 60 portion of one of the driving teeth.

Fig. 26 is a detail sectional view, taken on the line 26—26 of Fig. 24, looking in the direction of the arrows.

Fig. 27 is an elevational view of the upright kerf cutter and the means for operating it when two superposed columns of coal are cut from the coal face, as illustrated in 70 Fig. 7.

Fig. 28 is a sectional plan view of the construction shown in Fig. 27.

Fig. 29 is a sectional elevation, taken on 75 the line 29—29 of Fig. 28.

Fig. 30 is a side elevation of Fig. 28, with a portion of the cutter shown in section.

Fig. 31 is an enlarged sectional end elevation of a portion of Fig. 30, taken on the line 31—31, looking in the direction of the arrows.

Fig. 32 is a view of a portion of the ball bearing cage adapted to be used in the upright kerf cutter shown in Fig. 30.

Fig. 33 is an enlarged sectional view, taken on the line 33—33 of Fig. 30, looking in the direction of the arrows.

Fig. 34 is a sectional elevation of the mine car transporting mechanism, the left-hand portion being shown partly in section.

Fig. 35 is a transverse sectional elevation of the truck mechanism of the mine car transportation mechanism.

Fig. 36 is a plan view of the mine truck transportation mechanism shown in Fig. 34.

Fig. 37 illustrates one of the ends of the mine truck transportation mechanism, shown in Figs. 34 to 36, inclusive.

Fig. 38 is an enlarged sectional elevation of the roller bearing, adapted to the wheels of the transportation mechanism shown in Figs. 34 to 36, inclusive.

Fig. 39 is an elevational view of mechanism adapted to be added to the sides of the transportation mechanism shown in Figs. 34 to 36, inclusive, to hold blocks of coal in place.

Fig. 40 is an end view of the construction 110 shown in Fig. 39, with the addition of mechanism for releasing the devices which hold the blocks of coal in place.

Fig. 41 represents, in sectional plan view, a portion of the mine with my improved mining and loading apparatus, arranged for operation at the rear end of a pillar in a retreating system of coal mining, while subsidence of the roof is controlled to carry out 115 my improved method of mining.

Fig. 42 represents diagrammatically the switching by means of cable haulage mechanism, of the mine truck transportation apparatus illustrated in Figs. 34 to 36, inclusive.

Fig. 43 is a plan view of a modified loading apparatus, particularly adapted for moving blocks of coal from the working face upwardly in the direction of a pitched vein.

Fig. 44 is a sectional elevational view of 130

Fig. 43, taken on the line 44—44 of Fig. 43, looking in the direction of the arrows.

Fig. 45 is a transverse sectional elevation of one of the units of the mine track transportation mechanism, with belts both above and below the blocks of coal.

Fig. 46 is a view taken on the line 46—46 of Fig. 43, looking in the direction of the arrows.

Fig. 47 is a plan view of mining mechanism adapted to simultaneously cut columns of coal and foreign material, and load the coal without interference from the dislodged foreign material.

Fig. 48 is a sectional elevation, taken on the line 48—48 of Fig. 47, looking in the direction of the arrows.

Fig. 49 is a transverse sectional elevation, taken at 49—49 of Fig. 47, looking in the direction of the arrows.

Fig. 50 is a sectional elevation of a portion of a reel, showing a modification of Fig. 19 and adapted to wind simultaneously a belt and a rope.

Fig. 51 illustrates diagrammatically the method of mining coal particularly adapted to the system shown in Fig. 47, wherein columns of coal and foreign material are cut simultaneously.

Fig. 52 represents in plan view a system of conveyors combined with the mining mechanism, when the latter is employed for cutting coal and foreign material and separating and loading both of them.

Fig. 53 is a sectional view, taken on the line 53—53 of Fig. 52, looking in the direction of the arrows.

Fig. 54 is a sectional view taken on the line 54—54 of Fig. 52, looking in the direction of the arrows.

Fig. 55 is a side elevation of an attachment adapted to be connected to the forward end of the mining machine shown in Fig. 1, after certain parts have been removed.

Fig. 56 is an enlarged view of the lower stripping mechanism shown in Fig. 55, certain portions being shown in section.

Fig. 57 is a plan view of the lower portion of the apparatus shown in Fig. 55, and is taken on the line 57—57 of Fig. 55.

Fig. 58 is a sectional view of the mine chamber after two superposed columns have been cut, and illustrates the manner in which the stripping of the floor and roof layers of coal is performed, while such superposed columns are being cut, and additional floor and roof coal layers are being left.

Fig. 59 is an elevational view diagrammatically illustrating the system adapted for the mining of very thick veins of coal in terrace formation.

Fig. 60 is a plan view, taken on the line 60—60 of Fig. 59.

Fig. 61 is a diagrammatic elevation of

framework adapted to a system of mining very thick veins of coal.

Fig. 62 is a diagrammatic illustration of a system of mining very thick veins of coal having considerable pitch.

Fig. 63 is an elevational view of means for unloading coal from mine truck transportation mechanism, such as that illustrated in Figs. 34 to 36, inclusive, where the mine track is on an incline.

Fig. 64 is a plan view of the left-hand portion of the construction shown in Fig. 63.

Fig. 65 is a plan view of a flexible belt composed of strands of rope adapted to be hauled into the train illustrated in Figs. 34 to 36, inclusive.

Fig. 66 is a view of a reel adapted to be placed on the winding mechanism shown in Fig. 15, so as to operate the rope carrier illustrated in Fig. 65; and

Fig. 67 is a sectional view of Fig. 66, taken on the line 67—67, looking in the direction of the arrows.

Referring to Fig. 1, 68 designates the frame on which the mining mechanism is mounted. Mounted on this frame are three horizontal rotary kerf-cutters 69, 70 and 71, respectively located at the roof, midway between the roof and floor, and at the floor. The roof kerf-cutter 69 is mounted on an auxiliary frame 72, which is adjustable in elevation along the guide-ways 73 and 74, as shown in Fig. 3. The intermediate kerf-cutter 70 is likewise mounted on the auxiliary frame 75, which is adjustable in elevation along the guide-ways 76 and 77. In a similar manner the floor kerf-cutter 71 is mounted on the auxiliary frame 78, which is adjustable in elevation along the guide-ways 79 and 80.

The upright kerf-cutter 81 is so mounted on the framework 68 as to occupy a kerf-cutting position in a plane extending tangentially to the inner cutting edges of the three horizontal kerf-cutters, as illustrated in Fig. 1. The vertical kerf-cutter 81 is mounted on a flat frame 82 in the plane of the intermediate kerf-cutter 70. The flat frame 82 is connected to the auxiliary frames 83 and 84, which are mounted in guide-ways 85 and 86 in the frame work 68, so that the flat frame 82 may be adjusted in elevation in accordance with the elevation of the intermediate kerf-cutter 70.

Each of the horizontal cutters is rotated, or driven, by means of an individual electric motor. The electric motors for driving the horizontal kerf-cutters 69, 70 and 71 are mounted in the frames 72, 75 and 78, respectively. The vertical kerf-cutter 81 is driven by two electric motors mounted, respectively, in the frames 83 and 84. Any suitable and well-known system of motor-

control may be used for starting, stopping and controlling the speed of each of the aforesaid electric motors.

Detachably connected at 85, to the forward 5 end of the frame 68 is a skid-frame 86, which is adapted to rest on and slide over the mine floor. It will be seen by referring to Fig. 3 that the frame 68 is provided with a skid 87, which cooperates with the skid 88 to support the machine on the mine floor for feed rectilinearly along the mine wall. Suitable roof-jacks 89 may be arranged in spaced-apart relation at such a distance from the mine wall as to serve as guides during the 10 feeding of the mining mechanism.

To effect the feeding of the mining machine rectilinearly along the mine wall a motor-operated winding mechanism, illustrated at 90 in Figs. 1 and 3, is mounted at 20 the forward end of the frame 86'. The free end of the rope 91 extends from this winding mechanism to an anchorage 92. Therefore when the winding mechanism 90 is operated to exert a pull on the rope 91, the whole 25 machine will be fed along the mine wall during the rotation of the kerf-cutter so as to effect the cutting of suitable columns of coal, as illustrated in Fig. 7.

Details of the horizontal kerf-cutters 69, 30 70 and 71, together with the means for driving the same, are illustrated in Figs. 20 and 21. In other words, Figs. 20 and 21 illustrate the type of horizontal cutter unit which may be used on the mining machine 35 shown in Figs. 1 and 3. Assuming that the mechanism shown in Figs. 20 and 21 represents the horizontal floor kerf-cutter, it will be seen that the motor-frame 78 is detachably connected at 93 to a supporting frame 94, to which may be bolted, at 95, the circular frame 96 of the horizontal kerf-cutter 71. It will be seen that the kerf-cutter in 40 its entirety may be removed from the frame 94 by removing the bolts 95.

45 The motor armature shaft 97 is provided with a pinion 98 which meshes with a gear 99, the latter in turn meshing with the internal annular gear 100, which is mounted on a bearing 101 within the frames 78 and 94, as shown in Fig. 21. The annular gear 100 is in fact connected to a sleeve 102, which is journaled on the bearing 101. This annular sleeve 102 is provided with sprocket-teeth 103, which are adapted to mesh with the series of lateral openings 104 in the ring-cutter-frame 105.

Extending radially from the ring-cutter-frame 105 are a plurality of cutter-bits 106 secured in place by the set-screws 107. 60 While only two cutter-bits are shown in Fig. 20, it should be understood that they are mounted at intervals entirely around the ring-frame 105 in every position where the notch 108 is shown in Fig. 20.

65 When the cutter-bits 106 become dull and

it is desired to re-sharpen the same, the entire disc-cutter may be removed by loosening the bolts 95. The hand-hole 109 is provided in the plate 96 for convenience of handling the disc-cutter after being removed from the 70 frame 94.

Provision is also made for removing the ring-cutter-frame 105 in sections from the plate 96 without unbolting the latter from the frame 94. For this purpose interlocking 75 means 110 is provided between the ring-cutter-frame 105 and the inner ring 111. The ring 105 is held in interlocking relation with the ring 111 by means of the keys 112, 112'. It should be noted that the ring 111 80 is connected to the plate 96 by means of the rings 113, 114, between which is located the ball-bearing 115. The peripheral portion of the ring 111 is provided with circumferential projections, some of which extend in a clockwise direction and others of which extend in an anti-clockwise direction. The sections 116, 117, 118 and 119 of the ring-cutter-frame 105 are also provided with interlocking projections adapted to fit those on the ring 111. It can be seen by referring to Fig. 20 that when the key 112 is removed the sections 116 and 119 may be moved toward each other so as to release them from the interlocking projections on the ring 111. In 85 like manner, when the key 112' is removed the sections 117 and 118 may be moved toward each other so as to release them from the ring 111. In this way the ring-cutter 90 100 105 may be removed from the supporting frame in four sections and therefore conveniently transported, together with the dull bits therein, to the place where the bits may be re-sharpened or replaced by newly sharpened bits.

After the sections 116, 117, 118 and 119 have been removed, with the dull bits therein, other like sections, with sharpened bits therein, may be immediately substituted for the removed sections. The sections with the sharpened bits therein are placed on the ring 111 in interlocking relation therewith and the keys 112 and 112' are driven into place so as to securely hold the sections rigidly connected to the ring 111 to rotate therewith 110 on the ball-bearings 115 around the circular cutter-head 96.

By referring to Fig. 23 it will be seen that the lateral walls or surfaces of the openings 104 in the cutter-ring 105 are provided with bevels 120 and 121, so as to co-operate with the bevelled surfaces of the sprocket-teeth, or gear-teeth, 103 which are mounted on the rotatable sleeve 102. It should also be noted that the cutter-ring 105 itself is 120 provided with the gear-teeth, or sprocket-openings, for the driving-gear 103. The gear-teeth are in the detachable sections and by providing a circular line of drive at the outer peripheral portion of the kerf-cutter 125 130

the latter may be fed into the mine wall to cut a kerf substantially deeper than the radius of the kerf-cutter; for instance, as illustrated in Fig. 20, the kerf-cutter may cut 5 a kerf approximately three-fourths of the diameter of the kerf-cutter.

In Figs. 24, 25 and 26 are shown, in enlarged detail view, mechanism for increasing the effectiveness of the interlocking connections between the sections of the ring-cutter frame 105 and the ring 111. Fig. 26 is a section, taken on line 26—26 of Fig. 24, looking in the direction of the arrows, and shows a pin 122 cylindrical in shape and adapted 10 to fit in the semi-cylindrical recess 123 in the section 118. The pin 124 is similarly arranged by being driven into a cylindrical recess in the ring 111. It should be understood that at each interlocking connection 15 between the ring 111 and the four sections pins similar to those designated 122 and 124 may be located in position to have semi-cylindrical projections to fit in semi-cylindrical recesses corresponding to that 20 designated 123 in Fig. 26. When the key 112' is driven into the position illustrated in Fig. 24 the interlocking connection illustrated in Fig. 26 will effectually prevent movement of the cutter-ring-section trans- 25 versely of the frame 96. In this manner the interlocking connections between the four sections and the ring 111 prevent relative movement, either circumferentially or laterally. After the key 112' has been driven 30 into the position illustrated in Fig. 24 it may be locked in place by the pin 125, extending through the section 118 and a cylindrical recess in the key 112'.

The vertical kerf-cutter 81, and the means 40 for driving it, are illustrated in Figs. 27 to 33, inclusive. The frames 83 and 84, shown in Fig. 27, are electric motor frames, bolted, respectively, at 126 and 127 to the horizontal flat plate 82 which is adapted to be moved 45 along the horizontal kerf produced by the horizontal intermediate kerf-cutter 70. The motor-shafts 128 and 129 are provided with pinions 130 and 131 which mesh, respectively, with gears 132 and 133. The latter 50 are connected to transverse shafts 134 and 135, which extend through the flat plate 82, as shown in Figs. 27, 28 and 29. At the outer ends of the shafts 134 and 135, as 55 shown in Figs. 28 and 29, are driving gears 136 and 137, which may be formed integral with the shafts 134 and 135, if desired. The driving gears 136 and 137 are spaced apart, as shown in Fig. 29, in position to mesh with the internal annular gear 138, which is riveted 60 to the ring 139, mounted to rotate on the ball-bearings 140 around the ring 141, which is riveted at 142 to the central plate 143. The vertical plate 143 is circular in form, as shown in Fig. 29, but it is rigidly connected 65 to the plate 82 and may be formed integral

with the latter. By referring to Fig. 30 it will be seen that the plate 143 may have an enlarged ring portion 144, as shown in Fig. 30. The sectioning of the parts 82, 143 and 144 in Fig. 29 indicates that these parts 70 may be formed in one casting and provided with the circumferential grooves indicated in Fig. 30. The gear 138, secured to the ring 139, fits in the outer peripheral groove of the plate 143, 144. The ring 141, the ball-bearing 140 and the inner portion of the ring 139 fit in the groove 145, as shown in Fig. 30. A plate 146 covers the ball-bearing which is illustrated in Figs. 32 and 33, as comprising a ball-bearing-cage 147 and the 80 balls 140.

On the peripheral portion of the ring 139 are interlocking projections 148, which are adapted to fit into corresponding interlocking recesses 149 in the ring-cutter 150, which 85 comprises a frame divided into six sections designated, respectively, 151, 152, 153, 154, 155 and 156, as shown in Fig. 29. Interlocking connections for the upright kerf-cutter, shown in Figs. 27 to 30, inclusive, 90 may also be provided similar to those shown at 122 and 124 in Figs. 24 and 26, to prevent lateral movement of the ring sections from the ring 139.

The ring sections 151 to 156, inclusive, 95 may be moved into interlocking relation with the ring 139 by means of the rotary cams shown at 158, 159 and 160 in Fig. 29. Each of these cams may be rotated manually by means of a socket wrench applied at the 100 square ends 161, 162 and 163 of the shafts to which the cams are connected. When these cams are thus rotated they act as eccentrics to spread apart the adjacent sections so as to move them into interlocking relation 105 with the ring 139, as shown in Fig. 29. It should be noted that each of the eccentric cams, 158, 159 and 160, is mounted to rotate outwardly, or toward the circumference of the ring-cutter, when the sections are moved 110 into interlocking relation. This arrangement is preferred because during the operation of the kerf-cutter in its entirety the centrifugal force will not tend to release the cams, but on the contrary will tend to tighten 115 them more firmly in place so as to maintain the aforesaid interlocking relation. If desired, a spring-pressed locking-pin may be provided for each of the cams, as illustrated at 164 in Fig. 27, to hold the cams in locking position, but permitting them to be released when the socket-wrenches are applied, as above explained.

It is preferred to provide two electric 125 motors 83 and 84, spaced apart as shown in Figs. 27 and 28, each connected to its pinion, which meshes with the internal annular gear 138. The shafts 134 and 135 are journaled in brass or bronze bushings 165, 166, 167 and 168. By providing a plurality of motors 130

- the driving power, applied to the ring-cutter, is distributed over opposite portions of the annular gear 138 and, moreover, each electric motor will do its share of the work required without great accuracy in the gearing, illustrated at 136, 137 and 138. Furthermore, by providing a plurality of motors to drive the upright rotary kerf-cutter the motors may be made smaller than if one alone were used, and this enables the machine to be made more compact because the available space, as shown in Figs. 1 and 3, is better adapted for small sized motors. The distribution of the application of the power to the upright kerf-cutter will also prevent undue strains on the machine and facilitate the maintenance of the rotation of the upright kerf-cutter in a true vertical plane, as shown in Fig. 7.
- 20 The distribution of the application of the power to the upright kerf-cutter may be further carried out with three horizontal columns, as illustrated in Fig. 9, by the blocks 169, 170 and 171. In Fig. 11 the vertical kerf-cutter 81 is mounted to be driven by four electric motors 83', 84' and 83'', 84'', mounted on the horizontal flat frames 84' and 82'', which are connected to the main frame 68 in position to extend along the horizontal kerfs 172 and 173, shown in Fig. 9. In Fig. 12 the motors 84' and 84'' are shown in side view with the supporting plates 82' and 82'' extended a sufficient distance to the right to permit the passage of the columns of coal 169, 170 and 171, shown in Fig. 9. It should be particularly noted that the motors shown in Fig. 11 are connected through shafts in the plates 82' and 82'' to driving gears distributed at four different locations around the annular gear illustrated in detail at 138 in Fig. 29.
- 45 Fig. 10 illustrates diagrammatically the cutting of four superposed columns of coal, 174, 175, 176 and 177, which can be produced by one vertical kerf-cutter 81, extending from the floor to the roof of the mine chamber and supported by three horizontal spaced-apart plates, instead of two, as shown in Fig. 11. In the arrangement for cutting the columns of coal shown in Fig. 10 the driving connection to the annular gear, shown at 138 in Fig. 29, is distributed along six different locations, there being preferably six motors arranged in pairs in the same manner as the two pairs of motors illustrated in Fig. 11.
- 60 Fig. 13 illustrates diagrammatically the cutting of superposed blocks of coal 178, 179, 180 and 181, with the horizontal kerfs so arranged as to maintain within the cut columns the bands of foreign material, such as illustrated at 182 and 183 of Fig. 13. It will be noted that the intermediate horizontal kerfs 184, 185 and 186 are spaced apart unequally, which may be effected by mount-
- ing each plate, such as those illustrated at 82' and 82'' in Fig. 11, at various elevations. Each plate, with its pair of motors and driving connections, may be mounted so as to be individually maintained in mesh with the 70 annular gear 138, illustrated in Fig. 11 by the dotted circle 138'. The advantage of producing the columns of coal, as illustrated in Fig. 13, is to retain the bands of foreign material in the blocks of coal removed from the mine so that the foreign material may be dislodged more conveniently above ground. In other words, it is preferred to avoid cutting of kerfs through bands of foreign material and thus preventing cuttings of foreign material from mixing with cuttings of coal.
- 80 Referring again to Figs. 1 and 2, it will be seen that extensible loading apparatus is connected to the mining machine in such a manner as to extend around the corner into an entry at right angles to the path of the mining machine. Detachably connected to the frame 68 at 187 and 188 is a frame 189, which is provided with a curved chute 190, as illustrated in Fig. 1, in position to receive and deflect the upper column of coal so as to break such upper column into smaller pieces, as illustrated at 191, and direct such blocks of coal away from the mine vein 95 and permit such blocks to descend to a lower level so as to be received by a traveling belt 192, and be carried by the latter into the chute 193 so as to impinge against the vertical arcuate wall 194, as shown in Fig. 2. 100 It should be understood that the continuous forward feed of the mining machine, by exerting the pull on the rope 91, will cause the columns to extend rearwardly. Therefore, the curved walls of the chute 190 will be 105 pushed against the upper column of coal. In most instances both the upper and lower columns of coal will be broken down into blocks by their own weight, as the feeding of the mining machine progresses. The 110 main object of the upper curved chute 190 is to direct the dislodged material onto the travelling conveyor belt 192, but it may also have the function of deflecting the upper column to assist in breaking the same into 115 blocks, as illustrated in Fig. 1.
- 120 As shown in Fig. 3, the frame 189 may be supported by a wheel 195 pivoted to a frame 196 attached to the bottom rear portion of the frame 189. The chute 190 may be extended downwardly any desired distance, so as to direct the blocks of material onto the belt 192. The frame 196 is provided with a swivel 197 so that the wheel 195 can readily follow the direction of feeding travel of 125 the mining machine while the rear end of the frame 189 is supported in elevated position with sufficient clearance above the belt 192.
- 130 The belt 192 is wound on and paid out

from the winding mechanism 198, mounted on the forward frame 86. The belt 192 preferably extends to the floor of the mine chamber and along the bottom of the supporting frame 68 in position to receive the cuttings from the horizontal kerf-cutters. By referring to Fig. 1 it will be seen that the inner edge 199 of the belt 192 is over-lapped by the circular rotary cutters 69, 70 and 71. The belt 192 is so directed along the guide-ways 200 on the frame 86 as to hold the belt flat on the floor under the cutters of the floor kerf-cutter 71. The belt 192 is preferably composed of steel,—thin, flexible, hard and durable. The cuttings received by the belt 192 are illustrated in Fig. 3 at 201.

The belt 192 extends rearwardly to the winding mechanism 202, shown in Fig. 2, but it should be understood that the belt 192 is not positively driven by either the winding mechanism 198 or the winding mechanism 202, while the mining operation is taking place along the working face, except that the winding mechanism 202 may be operated whenever desired to keep the belt 192 taut, or to convey some of the blocks of dislodged coal on to the loading apparatus shown in Fig. 2. In any event, as the mining operation proceeds along the working face, as illustrated diagrammatically in Fig. 41 at 203, the winding mechanism 198 is paying out the belt 192 whether the winding mechanism 202 is also operated, or not.

In order to provide a vertical wall for the blocks of coal a belt 204 is paid out from the winding mechanism 205 mounted at the rear end of the supporting frame 68, as shown in Figs. 1 and 3. The belt 204 is extended to the winding mechanism 206 on the frame 207, as shown in Fig. 2. The winding mechanism 206 may be secured to the frame 207, as indicated at 208. The frame 207 may be anchored by means of the roof-jacks 209 and 210. As the mining machine is fed along the mine wall, as shown diagrammatically in Fig. 41, the vertical belt 204 is paid out by the winding mechanism 205, but the winding mechanism 206 is not intended to positively drive the belt 204 during the mining operations, except at intervals to hold the belt 204 taut so that it will prevent the blocks of coal 191 from going off the belt 192.

The lower column of coal, after being cut, may break into smaller pieces by its own weight, or otherwise be broken into sections of desirable length. These sections have extending under them a conveyor comprising a plurality of spaced-apart wire ropes or cables 211 which are paid out from winding mechanism, illustrated at 212 in Fig. 1. This winding mechanism is shown more clearly in Fig. 7. The ropes 211 extend through grooves, or cylindrical curved guide-ways, in the plate 213 so as to direct

the ropes to extend parallel to the mine wall, the winding mechanism 212 being mounted on the frame 68 to operate on an axis parallel to the mine wall. The plate 213 may have an upper extension 214 adapted to travel along the lower portion of the kerf cut by the vertical kerf-cutter 81. An additional rope may be attached at 215 to the vertical extension 214.

By referring to Fig. 2 it will be seen that the ropes 211 extend to a winding mechanism 216 mounted on the base plate 207. During the operation of the mining machine, as illustrated in Fig. 41, the winding mechanism 212 is arranged to pay out the ropes 211, but at such time the winding mechanism 216 is not operated except to maintain the ropes 211 taut, or to move them toward the right, as viewed in Fig. 2, to relieve the tendency at certain times of the blocks to spread apart and therefore require more room. In this respect the operation of the winding mechanism 216 is similar to that of the winding mechanism 202 in keeping the rope and belt conveyors taut and keeping the blocks of coal in alignment in readiness to be loaded into the train, or mine cars, after the mining operation has been completed and the mining machine is in readiness to be retracted.

The apparatus for loading the blocks of coal into the mine truck transportation mechanism shown in Figs. 34 to 36, inclusive, is shown in Figs. 1 and 2, particularly the latter. The receiving chute 193 comprises spaced-apart upright arcuate walls 194 and 217. The arcuate wall 217 is rigidly connected to the bottom of the chute and together with this bottom is detachably connected at 218 (Fig. 4) to the rear end of the base frame 219, shown in section in Fig. 5. It should be understood that Fig. 5 is a sectional elevation of Fig. 2 on the line 5—5, looking in the direction of the arrows. Fig. 4 is a sectional elevation of Fig. 2 on the line 4—4, looking in the direction of the arrows. The arcuate wall 194 is shown in elevation, however, for the sake of clearness, since this is a separate casting detachably connected at 220 to the frame 221, on which the winding mechanism 222 is mounted. The frame 221 may be rigidly connected to the base frame 219, but is spaced above it to the point 223 to permit the passage of the ropes 211 and the belt 192. It should also be particularly noted that the passageway beneath the frame 221 is not only open at the sides, but also at its rear end, so that the frame 219 may be pulled forwardly away from the belt 192 and the ropes 211 without disturbing the latter.

The frame 221, which is rigidly connected to the frame 219, or formed integral therewith, is provided with a forwardly extending platform 224 which carries the exten-

sion 194' of the upright arcuate chute-wall 194. The upright arcuate walls 194 and 194' are separate pieces, but secured in arcuate alignment at 226, as shown in Figs. 2 5 and 5. It can readily be seen, by referring to Fig. 2, that the upper surface of the casting or base-frame 219, at 227, merges into the upper surface of the platform 224 and that the plate 224 may be an integral rear- 10 ward extension from the forward portion of the base frame 219. In this manner the space beneath the platform 224 and beneath the winding mechanism 222 may be used for the passage of the belt 192 and the ropes 15 211 in a very compact arrangement of the various winding devices shown in Fig. 2. The platform 224 may thus serve as an operating platform when desired for the attendant controlling the various winding devices 20 above referred to.

As shown in Figs. 2 and 5, the frame carrying the winding mechanism 222 may be anchored by means of the roof-jack 229. The winding mechanism 222 is adapted to 25 pay out a belt 230, which is guided under the platform 224 and along the upper inclined surface 231 on the base frame 219. Attached to the free end of the belt 230, as shown in Fig. 2, is a cross-piece 232 to 30 which is adapted to be connected a hook 233 connected to the free end of the rope 234. The rope 234 is directed around pulleys 235 and 236 to the winding mechanism 237, mounted on the base plate 207. The direction pulleys 235 and 236 are pivoted on a frame 238, which may be held in fixed position by means of the roof-jack 239, shown 35 in Figs. 2 and 5.

By means of the mechanism shown in 40 Fig. 14 the cross-piece 232 may be detachably connected to the belt 230. The latter is preferably formed of flexible sheet steel of sufficient hardness and durability to efficiently load coal as desired. At the end of 45 the belt there is a series of perforations 240 into which locking pins 241 may be inserted, as shown in Fig. 14. These locking pins are mounted on the narrow plate 242, which is hinged at 243 to the cross-piece 232. By 50 means of a spring-pressed latch 244 the locking plate 242 may be held in such position as to hold the rope 234 and the cross-piece 232 securely connected to the belt 230. The cross-piece 232 may be readily detached from 55 the belt 230 by releasing the latch 244. As shown in Fig. 2, two of such latches may be arranged in spaced-apart positions at 244 and 244'. The advantage of this arrangement is the ability of the rope to equalize its 60 pull over the entire width of the belt, when the belt is pulled forwardly to load the coal onto a platform 245, mounted on a truck 246, as shown in Fig. 5. Furthermore, when it is desired to retract the belt 230 by pulling 65 it out from under blocks of coal, the cross-

piece 232 should be detached so that the free end of the belt will freely slip under the blocks of coal. As above explained the cross-piece 232 may be readily detached by 70 releasing the latch mechanism and lifting the locking-plate 242, which may be done by grasping the projecting edge 247.

Each of the winding devices, illustrated diagrammatically in Figs. 1, 2 and 3 at 90, 198, 205, 212, 206, 202, 216 and 237, may be 75 constructed as illustrated in Figs. 15, 17 and 18. A supporting frame 248 has mounted thereon upright end-plates 249 and 250, as shown in Fig. 15. The peripheral portions of the end supports 249 and 250 may be 80 connected by curved sectional plates 251, spaced apart so as to provide opening 252 and 253 for the passage of a belt or ropes wound on the reel within the frame-work. The belt or ropes may also be paid out from the lower 85 portion of the drum in either direction, depending upon the direction of winding of the belt on the reel.

Rigidly secured to the end-plate 249 is 90 the hollow interior frame 254, in the center of which is journaled the armature shaft 255 of an electric motor. The other end of the shaft is journaled in the bearing 256 of the spider-frame 257 at the central portion of the end plate 249. The frame 254 may 95 constitute the field of the electric motor, having the pole pieces 258, the armature 259 and the commutator 260.

Secured to the peripheral portion of the circular field frame 261 is an internal 100 annular gear 262 with which is adapted to mesh a gear 263. The latter is mounted on a shaft 264 which is journaled in a frame 265 provided with a counter-weight 266. The circular frame 265 is keyed to the extension 267 of the motor armature shaft. Therefore when the motor operates the frame 105 265 rotates with the armature shaft 255 and rolls the gear 263 around the annular gear 262 while the latter remains in fixed 110 position.

Also mounted on the shaft 264 to rotate therewith is a gear 268 which meshes with the internal annular gear 269 mounted on the peripheral portion of the circular plate 115 270. The central portion of the plate 270 is provided with a short shaft 271 concentric with the axis of the motor armature shaft, and journaled in ball-bearings 272 at the central portion of the end plate 250. It 120 will thus be seen that when the motor is operated the gears 263 and 268 are rotated bodily, as well as on their own axis, and their weight is counter-balanced by the counter-weight 266. Inasmuch as the motor armature rotates at a comparatively high speed the counter-weight 266 tends to prevent undesirable vibration.

Securely connected to the peripheral portion of the circular plate 270 is a winding 130

drum 273 which is journaled to rotate around the motor frame on the ball-bearings 274 and 275. The winding drum 273 is therefore rigidly connected to the circular plate 270 5 to rotate therewith and such rotation is concentric with the axis of the motor armature. The winding mechanism and the means for operating it are, therefore, arranged in very compact relation. It will be seen that the 10 motor and the driving mechanism are mounted entirely within the space enclosed by the winding drum. The driving mechanism comprises differential gearing in that the gears 263 and 268 have a different number 15 of teeth. For instance, if the gear 268 has one more tooth than the gear 263, each rotation of the motor armature shaft will rotate the drum 273 only a distance measured by one tooth on the gear 262. In this manner 20 a slow and powerful rotation of the drum 273 may be secured.

The reel 273' is detachably mounted on the winding drum 273. The inner bore 276 of the reel 273' is made tapering to fit a corresponding tapering outer surface of the drum 273. The end plate 250 is detachable without disturbing the circular plate 270 and the winding drum 273, which are supported by the end plate 249. Without removing the 30 retaining devices 277 and 278 from the plate 270 the reel 273', with the belt 279 thereon, may be removed after the end plate 250 has been removed. When this has been done another reel such as that shown at 273" in 35 Fig. 19 may be placed on the winding drum 273. The reel 273" is provided with spaced-apart radial flanges 280 to divide the reel into sections to receive the ropes 211, such as illustrated in Figs. 1 and 2. In the same 40 manner reels may be provided which are particularly adapted for belts of various widths. By having the reels removable from the winding mechanism in the manner described belts needing repair may readily 45 be removed and transported in a compact form. New belts may be mounted on such reels and easily transported into the mine in compact form in readiness to be placed on the winding drum for use in the mining and 50 loading system, when desired.

The retaining devices 277 and 278 preferably fit into notches 281 and 282, respectively, so as to assist the friction of the tapering fit between the reel and the drum in 55 preventing the reel from slipping around the drum. When the mining machine is being fed along the mine wall and paying out a belt, such as that designated 192 in Fig. 3, it may be desired to hold the other end of 60 the belt on the winding mechanism 202 in Fig. 2 from being paid out. This may be done by suitable brake mechanism applied to the winding drum, or to the rim of the reel. In Fig. 15 I have shown a positive 65 stop in the form of latch mechanism com-

prising a lever 283, pivoted at 284 to the end plate 249 and provided at its upper end with a pivoted latch-bolt 285, which is adapted to slide into any one of a series of concentric perforations 286 in the rim of the reel 273'. 70

As shown in Fig. 16, the inner surface of the reel 273' may be provided with a key 287 fitting in a longitudinal slot in the outer surface of the drum 273. In this manner 75 the reel 273' will be positively locked against rotation relatively to the winding drum 273.

The end plate 249 is shown in Fig. 15 pivotally connected at 288 to the frame 248. This arrangement is preferred when another 80 winding device must be located closely adjacent the one shown in Fig. 15. Such a closely-adjacent additional winding device is illustrated by the dotted line 289. By loosening the bolts 290 the winding mechanism shown in full lines in Fig. 15 may be 85 tilted on the pivot 288 and thus enable the attendant to gain access to the winding device located at 289. In this manner the electric motor may secure attention, particularly with respect to the commutator and 90 parts associated therewith. When two winding devices are thus nested close together, their frames may be secured to each other, as illustrated at 291 in Fig. 15.

After the mining mechanism has been 95 fed along a mine wall to such a position that it is desired to retract the machine to a position to begin another cut along the mine wall, the frame 189, shown in Fig. 1, may be disconnected at 187 after the machine has 100 approached the right angle entry shown in Fig. 2. Such detachment of the frame 189 at 187 and 188 will enable the adjustment of the kerf-cutting mechanism shown in Fig. 1 in a narrow entry and positioned to 105 begin another mining operation along the working face of the coal pillar. After the cutting operation has proceeded a distance approximately equal to the length of the frame 189 and the upper column of coal has 110 been broken away manually, the frame 189 may be reconnected at 187 and 188. Of course, if the entry shown in Fig. 2 is of sufficient width, the frame 189 may be left 115 connected at 187 and 188 at all times. The mining machine may be retracted by adjusting the winding mechanism 90 so that the rope 91 will be free to be paid out when the machine is retracted. Inasmuch as the winding mechanisms 202 and 216 are similar in construction to that illustrated in Fig. 15, it can readily be seen that positive pulling 120 forces may be exerted on the belt 192 and the ropes 211, while they are being prevented from being paid out from the winding devices 198 and 212 by the positive latch mechanism illustrated at 283 in Fig. 15. The frame 207 being anchored by the roof jacks 209 and 210 and the winding devices 125 202 and 216 operated to pull the belt 192 130

and the ropes 211, the mining mechanism will be retracted toward the right angle entry shown in Fig. 2. At the same time the blocks of coal on the belt 192 and the 5 ropes 211, will be transferred into the chute 193 (Fig. 4) and directed by the upright curved walls 217, 194 and 194' (Fig. 2) on to the conveyor belt 230. During the retraction of the mining machine and the 10 transfer of the blocks of coal to the belt 230 the latter is moved along the entry shown in Fig. 2 by means of the winding device 237 and the rope 234 extending therefrom. It should be noted that the anchored 15 frame 238 which carries the direction pulleys 235 and 236 may be located at a distance from the winding device 237 to correspond with the length of the columns which have been cut. This can readily be 20 seen by referring to Fig. 2. The mining operation proceeds until superposed columns of predetermined lengths are mined from the working face and loading is effected upon retraction of the mining mechanism 25 by one continuous retracting movement to effect the loading of the coal in continuous streams into a train of what are, in reality, flexibly connected troughs along the bottoms of which the belt 230 is adapted to slide, 30 with the coal thereon.

When the mining mechanism is retracted toward the entry shown in Fig. 2 after having been operated along the rear end of a pillar, as shown in Fig. 41, the blocks of 35 coal of the lowermost column are carried by the ropes 211 so as to force such blocks of coal into the curved trough 193 and after leaving the latter the blocks of coal are received on the conveyer belt 230. Winding 40 devices 216 and 212 are located at the opposite ends of the ropes 211 and therefore when the winding device 216 is operated the ropes 211 may be paid out from the winding device 212 whether the framework 45 of the mining machine is stationary or in motion. But even when the winding device 212 is neither operated nor paying out the ropes 211 the winding device 216 may be operated to conform with the retracting 50 movement of the mining mechanism and during such operation friction between the ropes 211 and the blocks of coal is relied on to cause the blocks of coal to move along the chute 193. In any event the floor kerf-cutter 71 cuts a kerf of sufficient width to give ample clearance for the blocks of coal 55 to be received on the platform 213. When the blocks of coal are dislodged from a mine vein they will drop to a lower level onto the platform 213 and therefore any tendency for such blocks to slide toward the left relatively to the mining machine when the latter is retracted to the entry shown in Fig. 60 2 will be resisted by the projecting cutting bits of the floor kerf-cutter. The same is

true with respect to the upper column and the platform 82, and the intermediate horizontal kerf-cutter 70. However, with respect to the upper column the inclined chute 190 directs the blocks of coal by gravity to 70 a lower level where such blocks are received by the conveyer belt 192 and moved by the latter to the curved trough 193 shown in Fig. 2. The belt 192 being flexible will cause the lower forward end of the inclined chute 190 to act as a stop against any tendency of the coal being moved back upon the chute 190 when the mining mechanism is retracted and the coal moved along the curved trough 193. If desired, substantially all of the coal which has been cut may be loaded by the ropes 211 and the belt 192 into the curved chute 193 before the mining machine is retracted toward the entry 75 shown in Fig. 2. In such event during retraction of the mining machine only those blocks of coal which are carried on the framework would be retracted with the machine and this would readily be loaded after another operation across the mine wall was 80 well under way.

After the train has been loaded with the continuous series of blocks of coal, the cross-piece 232 is detached from the end of the belt 230 and the winding device 222 operated to pull the belt 230 out from under the blocks of coal, thus leaving the coal in the train for transportation along the mine track. The anchored frame 238 is located 100 in advance of the train of troughs or carriers before the rope 234 is connected to the belt 230.

The train of flexibly-connected troughs or carriers is illustrated diagrammatically at 292 and 293 in Fig. 41 and the units of such train are illustrated in detail in Figs. 34 to 105 36, inclusive. As shown in Fig. 34, a frame 294 of the truck 245 is mounted on wheels 295, which are adapted to travel on the rails 296 of a mine track. The truck frame 294 is provided with longitudinal passageways or recesses 297 to receive the coupling bars 298 and 299, respectively pivoted at their inner ends at 300 and 301 to the central portion of the truck frame 294. As shown in Fig. 35, the truck frame 294 may be made comparatively heavy so as to enable the wheels 295 to have sufficient traction on the rails to stay on the track. The truck frame 294 may be pivoted at 302 and 303 to the 110 axles 304 and 305, respectively. Springs may also be provided, as shown at 306 and 307, in Fig. 35.

Extending upwardly from the lateral central portions of the truck frame 294 are vertical side plates 308 and 309 at the upper ends of which are located longitudinal guides 310 and 311. Between the central portion of one truck frame and the central portion of the next adjacent truck frame is 115 120 125 130

connected a trough having spaced-apart side walls 312, 313, the ends of which are provided with vertical strips 314 and 315, which extend upwardly into the guides 310 and 311, as shown in Fig. 36.

The bottom of the trough is extended from the central portion of one truck frame to the central portion of the next adjacent truck frame. The bottom 316 of the trough having the walls 312 and 313, has its ends pivoted at 317 and 318 to the truck frame 294. While the coupling bar 299 is pivoted at its ends to the same bolts that the ends of the bottom 316 is pivoted it should be noted that the pulling strain between the trucks is taken by the coupling bar 299, and not by the trough, because the ends of the coupling bar fit closely on the pivot-bolts, while the ends of the bottom 316 have a loose fit, as shown in Fig. 34. This enables the trough to have an endwise movement relatively to the truck frame 294, thereby relieving the trough from pulling strain between the trucks.

By referring to Fig. 36 it will be seen that the ends of the bottom 316 of the trough having the walls 312 and 313 are provided with edges which extend angularly from the pivots 317 and 318 toward the ends of the truck that are adjacent each other. The adjacent ends of the bottoms of the troughs are therefore provided with angular faces between them so that the train of troughs may move laterally in both directions relatively to the trucks. This arrangement enables the train of wheel-mounted troughs to move around curves on the mine track. For instance, if the train 292, shown in Fig. 41, is hauled by the locomotive 319 onto the angular switch-track the ends shown at 320 and 321 in Fig. 36 are free to approach the ends 322 and 323, respectively, while the guides at the sides of the truck frames co-operate with the pivots 317, 318, 324 and 325 to hold the troughs in the desired relation to the truck frame. Meanwhile the blocks of coal are carried in continuous series extending along the train of trough sections. If desired, the ends of the bottoms of the troughs may be bevelled so as to facilitate the movement of the troughs on their pivots by scraping up from the floor of the truck frame any small particles of coal which may have become lodged thereon.

After the loading operation into the train of truck-mounted troughs has been effected, and the belt 230 has been retracted by the winding mechanism 222, the entire mining and loading apparatus should be shifted forward along the entry shown in Fig. 2 until the cutting apparatus will be in initial position preparatory for making another cut along the mine wall. For this purpose the hook 233 is connected to the pin 326,

shown in Figs. 1 and 3, after the rope 234 has been passed around the pulley 327, which is anchored by the roof-jack 328. When the frames 86' and 68 are moved into such position that they can be transferred transversely along the entry shown in Fig. 2 the frame 189 is swung on the pivot 188 in a clockwise direction so as to fold the frame 189 relatively to the frames 86', 68. Before the frames 86' and 68 are moved along the entry shown in Fig. 2 the rope 234 must be connected to the pin 329 (Fig. 2) on the frame 219, shown in Fig. 2. Then, while the frame 207 is anchored and the winding mechanism 237 operated to exert a pull on the rope 234, the frame 219 and the parts carried thereby, including the winding mechanism 222, after the roof-jack 229 has been released, may be moved forward along the right angle entry, leaving the ropes 211 and the belt 192 in their original positions, since the slot at the rear end of the frame 219, as shown in Fig. 5, permits the frame 219 to be moved forward away from the said ropes and the said belt.

After the frame 219 has been moved forward the frame 68 may be moved forward into the entry shown in Fig. 2, so that the bar 330 (Fig. 1) may be connected at 331 to the coupling shown at 332 in Fig. 2. The bar 330 is slidable longitudinally along the guide 333, which is fixed to the frame 68. Now upon releasing the jacks 209 and 210 and retaining the jacks 239 and 328 in anchored positions, the rope 234 may be passed around the pulley 327 and connected to the pin 326. Then, upon operating the winding mechanism 237, both the frame 207 and the entire mining machine will be moved rectilinearly along the entry shown in Fig. 2, so as to position the mining machine in readiness for making another cut along the mine wall. Of course when the frame 189 is folded, as above explained, and the frame 68 is connected to the frame 207 at 331, 332 the winding mechanisms for the ropes 211 and the belt 192 are so operated as to take up and hold taut said ropes and said belt to facilitate the adjustments above referred to. In the same manner the winding mechanisms for the belt 204 are operated.

After the mining machine has been moved to initial position preparatory to making a new cut the rope 234 is passed around the pulley 236 and thence to and around a pulley 334 to the pin 329. Now, upon anchoring the jack 210 and operating the winding mechanism 237 to exert a pull on the rope 234, the frame carrying the winding mechanism 222 may be moved rearwardly so that the base plate 219 will pass under the belt 192 and the ropes 211, as shown in Fig. 5. Then upon anchoring the jack 209 and the jack 229 the rope 91 may be connected to the

roof-jack 92, adjusted to a new position closer to the mine wall. While the mining operation is proceeding the roof-jack 239 and the roof-jack 328 may be moved forwardly along the entry shown in Fig. 2 and adjusted in position for the next loading operation.

As shown in Fig. 41, the mining operation may be carried on at the rear end of a pillar in a retreating system by having the mining machines move toward each other simultaneously, as shown at 203 and 335. A series of roof-props may be located at 336 and another series at 337. At 338 and 339 are shown additional roof-props which may be carried into the mine on mine cars, as shown at 340 and 341. As the rear end of the pillar is mined away the rear series of the roof-props 336 is removed and a new series placed in front of the series 337. In this manner the space where mining operations are proceeding is fully protected and the subsidence of the roof controlled so as to be confined to the space back of the roof-props.

The train of flexibly-connected troughs for the mining machine 335 is shown at 292 and this train may be hauled along the mine tracks 342 by means of the locomotive 319. In a similar manner the locomotive 343 may pull the train 293 along the mine track 344. The flexible connections on the upright axes between the train units readily permit the cars to pass around curves, or on and off switch tracks. Furthermore, if there are any irregularities on the tracks, tending to cause the train units to sway sidewise, the sides of the trough will bend to permit this. The troughs are made preferably of sufficiently thin plates of steel so as to be strong enough to handle the coal and at the same time have sufficient flexibility to permit lateral swaying of the cars without undue strain on the trucks and the connections thereto.

In Fig. 42 a hoisting apparatus is shown at 345 so that cables 346 and 347 may be used for hauling the trains 348 and 349 up and down steep grades, particularly in mines where the pitch of the mine vein is considerable, as illustrated in Fig. 62.

In Fig. 51 a method of mining is illustrated similar to that shown in Fig. 41, with the addition of central longitudinal entries 350 and 351 so as to permit the mining machines 335 and 203 to complete their cross-cuts at these entries 350 and 351. One of the mining machines may also mine the intervening pillar 352. In addition to facilitating the operation of the mining machines, the entries 350 and 351 also serve as ventilating passages, as indicated by the arrows. The fresh air may enter at 353 and pass along the entries into the space where the mining operations are being carried on, as

indicated at 354 and 355. The outgoing air, laden with coal dust, will pass into the entries 350 and 351 to the outlet at 356.

When the operations are being carried on so that the blocks of coal will have to be moved upwardly along a steep grade additions may be made, as illustrated in Figs. 43 to 46, inclusive. From the frame 68 extends a belt or rope 204' to a winding mechanism 357 mounted on the frame 219. The belt or rope 204' passes along the inner surface of the upright arcuate chute wall 194. In a similar manner a rope or belt 358 extends from the winding mechanism 359 along the inner surface of the upright arcuate chute wall 217 and is attached to the upright extension 214, which is shown more clearly in Fig. 7. When the blocks of coal are being loaded the winding devices 357 and 359 are operated simultaneously with the winding devices 202 and 216 to move the coal around the curved chute and upgrade into the train of troughs above described.

When the coal has been moved upgrade along the right angle entry shown in Fig. 43 it is also desirable to add a belt 360 by extending the same from the winding mechanism 361 over the top of the coal so as to co-operate with the belt 230 below the coal and thus move the latter upgrade into the train onto which the coal is to be loaded. For this purpose the frame 238' is provided with two pairs of pulleys. The pulleys 235', 236' are located in position to direct the rope, 234, whereas the pulleys 362, 363 are in position to direct the rope 364. Both of the ropes 234 and 364 are operated by the winding mechanism 237 and these ropes are connected, respectively, at 233 and 365 to the belts 230 and 360. When the winding mechanism 237 is operated the belts 230 and 360 are pulled forward simultaneously while being paid out by the winding devices 222 and 361.

In order to more effectively hold the coal in the train of troughs after the belts 230 and 360 have been retracted from the train by the winding devices 222 and 361, the upper longitudinal lateral pressure-bar, 115 shown at 366 in Figs. 39 and 44, may be employed. By referring to Fig. 45 it will be seen that these pressure devices may be in the form of plates 366 and 367, extending almost to the center of the truck, or the longitudinal center line thereof, and also extending almost the full length of one of the trough units. The plates 366 and 367 may be connected to angles, including the vertical strips or bars 368 and 369, 125 which are adapted to slide vertically along the guides 370 and 371. The upper ends of the vertical bars 368 and 369 are rigidly secured to the friction plate 366, as shown in Fig. 39. The lower ends of the bars 368 130

and 369 are connected at 372 and 373 to a leaf spring 374, which is so mounted at 375 as to exert a downward pull on the friction plate 366. The ends of the plate 366 are curved upwardly so that the coal may be moved under the plate with an upward lifting action against the downward pressure exerted by the leaf spring 374. The tension of the leaf spring may be adjusted 10 as indicated at 376. Adjustable stops are shown at 377 and 378 to limit the downward movement or lower position of the plate 366. By means of the stops 377 and 378 the bar 366 may be adjusted to a higher 15 initial position than the position shown in full lines in Fig. 39. In this manner the initial height of the friction plate 366 may be adjusted in accordance with the thickness of the blocks of coal.

20 As shown in Fig. 40, manually-operated releasing devices 379 and 380 may be provided at the sides of the trucks in position to engage laterally-extending flanges 381 and 382 to lift the friction plates 366 and 25 367 off the blocks of coal in the train troughs when it is desired to unload the coal from the train.

In Fig. 37 is illustrated the form of the troughs at the ends of the train. The end 30 troughs 383 are merely shorter in length, but are otherwise constructed and arranged as above described in connection with Figs. 34 to 36, inclusive. The train of troughs 35 may be open at its ends, but where the train is transported up grades in the mine vertical end gates 384 should be provided. These may be added by sliding them along the vertical guideways 385 and 386. In order to hold the short trough 383, shown 40 in Fig. 37, in fixed relation to the frame 387, set screws 388 and 389 are mounted in position to be engaged by the vertical angle iron strips 314' and 315'. The angle iron strips 314' and 315' are similar in construction 45 and arrangement as those designated 314 and 315 in Figs. 35 and 36.

In Fig. 38 is shown a roller bearing which 50 may be used for the wheels 295, shown in Fig. 34. This roller bearing construction comprises end plates 390 and 391, secured to the reduced extension 392 of the axis 304. Spaced apart bevelled bearings 393 and 394 are mounted on the ends of the extension 392. Cages 395 and 396 carry the rollers 55 397 and 398, which are frusto-conical in shape. These rollers are adapted to engage bevelled bearing surfaces 399 and 400 on the interior of the wheel 295. Circular gaskets 401 and 402 are mounted in circular recesses 60 at the sides of the wheel 295 in position to seal the peripheral portions of the plates 390 and 391 from the interior of the wheel 295. All of the parts within the wheel are secured to the axle 304 by means of the bolt 65 403. In this manner the wheel 295 may be

comparatively small and still be provided with the roller bearings shown. In fact the wheel, aside from the bearings, is composed of merely a rim. It should be understood that the end plates 390 and 391, together 70 with the bearings 393 and 394, are fixed to the axle 304 and remain stationary. The gaskets 401 and 402 co-operate with the plates 390 and 391 to retain lubricating material in the chamber in which the ball 75 bearings travel and also exclude dirt or foreign material from getting into said chamber from the exterior.

It should be particularly noted that not only is the bearing surface chilled or hardened, as indicated at 404, but the interior surface of the wheel rim is also chilled or hardened, as indicated at 405, so as to provide a durable bearing surface for each series of roller bearings 397 and 398. The aforesaid features are obtained in a small wheel with mechanism therein compactly arranged.

It will also be seen by referring to Fig. 38 that the wheel rim 295, including the hardened exterior 404 and 406 and also the hardened surfaces for the roller bearings, is integral throughout. Therefore, by hardening the race-ways for the rollers, the wheel 90 95 295 may be made smaller than when additional mechanism to form such race-ways must be placed within the wheel.

In Figs. 47 to 49, inclusive, the method of mining coal and foreign material separately is illustrated. The type of mining 100 machine shown in Figs. 1 and 3 is adjusted to cut superposed columns of coal and foreign material. In the plan view of Fig. 47 the chute 190 directs the blocks of coal away from the mine wall onto the belt 192'. 105 A rope 509 is connected to the forward end of the belt 192', and this rope extends to the winding mechanism 198. In order that the rope 509, as well as the belt 192', may be wound up by the winding mechanism 198 110 115 120 the reel shown in Fig. 50 is preferred. This reel 510 is provided with spaced-apart circular projections 408 and 409, adapted to be engaged by the belt 192' and thus leave a space beneath for the winding of the rope 509.

When the mining machine is operated along the mine wall the cutting operation is such that the upper column of coal is directed onto the belt 192' and the lower column of foreign material is left lying on the mine floor adjacent the unmined mass. On account of the series of blocks of foreign material, such as those designated "clay" in Fig. 47, being left lying on the floor they 125 would block the retraction of the mining machine unless they were moved out of the way. For this purpose a plow 410 is mounted on the forward end of the mining machine in position to engage the blocks of for- 130

sign material and move them a distance away from the mining machine approximately equal to the width of the last column cut. After the cutting operation is completed the mining machine may be moved away from the series of blocks 411 and toward the series of blocks 412. The space between the series 411 and the series 412 should be sufficient to provide ample clearance for the mining machine, when the latter is retracted toward the right angle entry and moved forwardly along the latter preparatory to making another cut.

In Fig. 52 the right angle entry is indicated at 413 and the system illustrated is similar to that shown in Fig. 47, with the addition of an elongated traveling conveyor 414 for receiving and conveying away the series 412 of blocks of foreign material. The belt-conveyor 414 may be operated by a winding device 415 at one end, and a winding device 416 at the other end. Winding devices 417 and 418 may also be added to operate the vertical belts 419 and 420, which are connected to fixed points 421 and 422, respectively. Upright arcuate chute walls may be provided at 423 and 424 for directing the blocks of clay, or other foreign material, onto the belt 425, which extends along the entry 413. A winding device 426 is in position on the frame 427 for operating the belt 425.

As shown in Fig. 53, the frame which carries the plow 410 is extended so as to serve as a support for the winding device 415. This extension frame is designated 428 in Fig. 53. As shown in Figs. 53 and 54, the winding devices 417 and 418 may operate ropes 419 and 420 in such a manner as to serve as guides to hold the blocks of material on the belt 414.

In Figs. 55 to 58, inclusive, mechanism is shown which is adapted to be mounted on the frame-work of the mining machine shown in Fig. 1. By detaching the frame 429 of Fig. 55 may be attached to the frame 68 so as to move bodily with the latter. A previous mining operation will cut superposed columns and leave layers of coal, as shown at 430 and 431 in Fig. 58. When the next mining operation takes place it is desirable to strip these layers from the floor and roof. This is done along the paths illustrated at 432 and 433 while the columns are being cut in the position shown in Fig. 58. That is to say, as the columns are being cut the roof and floor layers are being stripped to the left of such column, looking in the direction of the path of cutting travel of the mining machine.

Secured to the base-frame 429 is an upright auxiliary frame or plate 434 to which is pivotally connected at 435 the reciprocating dislodging apparatus 436. The details of this dislodging device are illustrated in Figs. 56 and 57 and comprise a frame 437 and a

reciprocating pick 438. When the electric motor 439 is operated the crank 440 is rotated to impinge at intervals against the lug 441, so as to move the pick 438 toward the right against the action of the spring 442. When the lug 441 is released the spring 442 will cause the pick-mechanism to fly forward to strike a hammer-blow against the roof layer of coal 430.

When the layer of coal 430 is dislodged in this manner it may be received by the chute 443 secured to the vertical plate 434 in such position as to direct the material on to the belt 192".

The pick machine operating at the roof is pivoted at 435 in inverted position, and its inclination may be adjusted by means of a socket wrench applied to the squared head 444 of the shaft which carries a worm 444' in mesh with a worm gear on the frame 437. The lower pick machine 445 is similar in construction and arrangement to that shown in Figs. 56 and 57. The bottom floor of the pick is serrated or provided with steps inclined so that when the pick moves forwardly with the quick motion effected by the spring 442 the plate 446 will move under the coal which has been lodged by such pick. The rearward movement of the plate 446 will be comparatively slow to effect rearward transportation of the dislodged coal toward the inclined surface 447. In this manner the floor layer of coal 431 may be dislodged and conveyed to the belt 192" by the reciprocating pick machine, which also acts as a conveyor.

When the construction shown in Figs. 55, 56 and 57 is attached to the mining machine frame 68 the winding device 90' may be mounted above the winding device 212 for operating the rope 91', which is adapted to be connected to the anchorage 92, shown in Fig. 1 for the purpose of feeding the mining machine along the mine wall. During this feeding operation of the mining machine proper the stripping mechanism shown in Figs. 55, 56 and 57 is also operated. While in Fig. 1 only three ropes 211 are shown there may be any number of closely adjacent ropes to form a belt. This is illustrated at 192" in Fig. 57, which is in position to operate along the path of the belt 192 of Fig. 1. In other words, when the construction shown in Figs. 55, 56 and 57 is used the mining machine retains the rope belt 211, but a belt such as that illustrated at 192" in Fig. 57 may be used in place of the belt 192, shown in Fig. 1.

In Fig. 59 a frame-work 448 is shown of such a width as to be movable along the entry 511 of Fig. 60. This frame-work 448 may be securely anchored in position by means of the roof-jacks 449, 450, 451 and 452. The roof-jack 453 is between the floor and roof of the mine chamber. The system

illustrated in Figs. 59 and 60 is particularly adapted for operating on very thick veins of coal, such as those which are more than 8 ft. or 10 ft. thick, say, for the sake of illustration, a 32 ft. vein of coal for the system shown in Fig. 59, in which event each terrace would be approximately 8 ft. thick and each of the four superposed blocks of coal nearly 2 ft. thick. The roof-jacks 449 and 450 may be sufficient to anchor the frame-work 448 after the mining operations are well under way. The roof-jacks 451 and 452 may then be located between the horizontal surfaces of the terraces and the roof 15 of the mine chamber. It should be understood that in Fig. 59 four systems of mining and loading machines are adapted to be operated at 454, 455, 456 and 457. The frame-work 448 is particularly adapted for 20 the purpose of initially supporting the mining and loading machines in proper position to start them along the respective terraces.

The type of mining and loading machines 25 may be as illustrated in Figs. 1 and 3, provided with three horizontal cutters each in addition to the floor and roof kerf-cutters, particularly for the location at 454. At 455, 456 and 457 only one floor kerf-cutter 30 and two horizontal kerf-cutters above the same need be used. In each mining machine, however, the vertical kerf-cutter should have a diameter approximately equal to the height of the step or terrace. The 35 blocks of coal are handled in pairs, as illustrated by the squares shown in dotted lines.

Fig. 60 is a plan view, as indicated by the section line 60—60 of Fig. 59, and illustrates diagrammatically the loading apparatus 40 shown more in detail in Fig. 2. The belt 230' is adapted to deliver the dislodged material to the chute 458, which is inclined downwardly, as shown in Fig. 59, and when the pivoted extension 459 is moved to the 45 dotted line position 460 the blocks of mined material from the uppermost terrace can be loaded into the train of troughs illustrated diagrammatically at 461.

In a similar manner the mining and loading mechanism operating along the position 455 will be able to deliver blocks of coal to the chute 462, mounted on the frame 448. When the inclined extension 463 is moved to the dotted line position 464 the blocks of coal 50 may be delivered to the trough train 461. The mining and loading mechanism operating along the position 456 delivers the blocks of coal to the inclined chute 465 and thence to the inclined extension 466, when 55 the latter is in the dotted line position 467. The mining and loading mechanism operating along the position 457 comprises a belt-conveyor which travels along the upwardly inclined chute 468. This belt may be drawn 60 along the bottom of the trough train, as

shown at 469. It should be noted that each of the chutes 458, 462, 465 and 468 is fixed to the frame 448, or is in fixed relation thereto during the operation of the mining and loading machines. When material is being delivered along the chute 468 the springs 470, 471 and 472 hold the chute-extensions 459, 463 and 466 in their full line positions, as shown in Fig. 59. In order to prevent interference of loading into the trough train 70 from the various mining and loading machines these extensions are moved to their dotted line positions, one at a time. That is to say, loading into the trough train takes place at any one time from only one of the 80 mining and loading machines. Which ever mining and loading machine has completed its forward path of travel may have its cut coal delivered to its respective inclined chute for loading into the trough train individually. Loading from the respective mining and loading machines may therefore be carried on independently from each machine.

After the mining machines have made 90 their complete cuts along the vertical walls of the terraces they may be brought back to initial positions on and adjacent the frame 448, so that when the latter is pulled forward by means of a rope attached at 473 95 the said machines will be adjusted to new initial operating positions. The mining and loading machines at the positions 454, 455 and 456 are always movable back onto the frame 448, while that located at 457 may 100 be supported on the floor and moved forward to a position adjacent the frame 448. It should also be noted that the belts which travel along the chutes 458, 462 and 465 are 105 respectively operated by the winding devices 474, 475 and 476, which are mounted on the frame 448. These belts are similar to that shown in Fig. 60 at 230', and each is adapted to be pulled along the bottom of the 110 trough train to load the coal thereon and then pulled out from under the coal to leave the latter loaded on the train. The belt 230', shown in Fig. 60, thus travels along the chute 458 and in like manner similar belts travel along the chutes 462, 465 and 115 468. The belt which travels along the chute 468 is shown at 469 and is operated by the winding device 477.

Fig. 61 represents an elevational view of 120 the construction shown in Fig. 59, but looking from the left toward the right, as viewed in Fig. 59. The location of the winding devices on the frame 448 corresponds to Fig. 59. The winding devices 474, 475, 476 and 477 may be centralized, as shown. The drum or winding device 202' is located 125 on the upper portion of the frame-work and corresponds to the winding device 202 of Fig. 60. In a similar manner the winding devices may be located at 478, 479 and 480.

The left-hand portion of Fig. 61 represents similar frame-work 448, operating at a different position in the mine, but it should be understood that it is preferred to operate the sets of mining machines from the spaced-apart frames 448 and 448' toward each other along the rear end of the pillar, such as that illustrated in Fig. 41. The terrace formation, as viewed in plan in Fig. 41, would then be downwardly toward the left-hand end of the view, the frames 448 and 448' being located in the entries 481 and 482, respectively. The mining machines would then initially start from the frames 448 and 448' and operate toward each other in a manner similar to the operation of the single mining machines 203 and 335, shown in Fig. 41. In other words, if the frame-work 448, shown in Fig. 59, were placed in the entry 482 the mining machines may be operated along terraces and a similar frame 448' placed in the entry 481 and the mining machines thereon operated along terraces in the opposite direction. In place of the entries 481 and 482 the entries 483 and 484 may be used, in which event the entries 481 and 482 would not be previously driven. At 485 in Fig. 61 the cutting of the blocks, or columns, is illustrated in dotted lines.

In Fig. 62 the system illustrated in Fig. 59 is shown applied to coal veins having considerable pitch and the coal cut is loaded into a trough train 486 movable upgrade. It will be seen by referring to Fig. 61 that at the roof of the mine chamber a shelf or terrace 487 may be formed for supporting a pipe 488 through which filling material may be passed into the mine, as indicated at 489 in Fig. 62. This material may be excavated from the surface at 490 and passed into the pipe 488 so as to take the place of the thick vein of coal removed and thus prevent caving in of the earth's surface above the place where mining operations are proceeding. This filling operation may also take place through the pipe 488', mounted on the terrace 487', as shown in Fig. 61.

Inasmuch as the loading takes place up grade in Fig. 62, winding devices 491, 492, 493 and 494 may be added to operate top belts, one of which is shown in Fig. 62 at 486, and the cars or trough train may be provided with the friction plates 367 shown in Fig. 45. There may also be a winding device located at 495 on the frame 496, and a vertical chute 497 used for directing the blocks of coal into an ordinary mining car 498. The trough train may be moved so as to occupy a position above the chute 497. In such event the curved chute 499, shown in Fig. 63, may be used to allow the coal to be directed into the vertical chute 497. The friction devices 367 may be released by a plurality of spaced-apart cams or levers 500

mounted on a rod 501 and rotated manually 65 by a wheel or crank 502. This construction is shown more in detail at 379 and 380 in Fig. 40.

In order that the trough train may clear the curved chute 499 the latter may be 70 hinged at 512 and provided with releasable retaining mechanism at 513, as shown in Figs. 63 and 64. When the trough train is moved along the uppermost portion of the inclined track the chute 499 may be released at 513 and swung laterally on the hinge 512 until the trough train reaches the position shown in Fig. 63 when the chute 499 may be swung back to its position over the track and the retaining device 513 re-engaged. 75

Fig. 65 represents a rope belt 503 which is adapted to receive the blocks of coal in a manner similar to the operation of the belt 230 of Fig. 2. The rope 234 may be used to pull the rope belt 503 along the bottom of the trough train with the coal mounted on the rope belt 503. After this has been done the ropes 504 and 234 are disconnected from the ends of the rope belt 503 and the latter left in the trough train with the coal thereon. This can be done because the rope belt 503 is flexible laterally and will therefore readily accommodate itself to the turning of the train units around curves in either direction. When the trough train is to be unloaded haulage ropes may be attached to the belt 503 so as to again use the latter to move the coal relatively to the trough train. This trough train is open at both ends after the end gates are removed, and therefore a haulage rope may be connected to either end of the rope belt 503 to drag the coal out of the trough train from either end thereof. The ropes of the rope belt 503 are made of durable material, such as steel, and the material handled being coal there will be sufficient lubrication furnished automatically. 90

The trough train per se and in combination with the parts associated therewith in the system of loading above described and shown in the drawings is claimed in my co-pending application, Serial No. 238,877, filed December 9, 1927, for an improvement in mine car loading apparatus, said application being filed as a division of this application. 100

The reel which is particularly adapted for operating the rope 504 to wind the rope belt by means of the winding mechanism shown in Fig. 15, is shown in Figs. 66 and 67. This reel designated 505 is provided with means at 506 for attaching the rope 504, which may be imbedded in the groove 507, so as to facilitate the winding and unwinding of the 110 cross-piece 508 and the ropes attached thereto. Such a reel may be used initially from which to unwind the rope belt 503 when the 120

coal is loaded onto the trough train and also when it is unloaded and is to be rewound into compact space to facilitate transportation in the mine, or elsewhere, where the 5 available space is very limited.

Obviously those skilled in the art may make various changes in the details and arrangement of parts without departing from the spirit and scope of the invention as defined by the claims hereto appended, and I 10 wish, therefore, not to be restricted to the precise construction herein disclosed.

Having thus fully described embodiments 15 of my invention and illustrated the same, what I desire to have secured by Letters Patent of the United States is:

1. In a mining and loading machine, the combination with mining mechanism, of 20 loading apparatus comprising an extensible belt conveyer connected to said mining mechanism to be extended by the feeding movements thereof, a deflector for directing dislodged material from the mining mechanism to said extensible belt conveyer, and means 25 for operating said mining mechanism while moving said deflector along a mine wall and extending said belt conveyer.

2. In mining and loading apparatus, the combination with a mining machine, of an 30 extensible conveyor connected to said mining machine to receive dislodged material therefrom, a chute for receiving material from said conveyor, and an additional extensible conveyor for receiving material 35 from said chute and transferring the same distant from said chute.

3. In mining and loading apparatus, the combination with a mining machine, of an 40 extensible belt conveyor connected to said mining machine in position to receive dislodged material therefrom, a winding mechanism therefor, a chute for receiving material from said conveyor, an additional extensible belt conveyor for receiving material 45 from said chute, and additional winding mechanism for operating said additional conveyor.

4. In mining and loading apparatus, the combination with a mining machine, of an 50 extensible belt conveyor continuously connected to said mining machine, winding mechanism therefor, means for receiving material from said belt conveyor, an additional extensible belt conveyor, additional 55 winding mechanism for said additional belt conveyor, and means for receiving material from said additional belt conveyor.

5. In a mining and loading machine, the combination with mining mechanism for 60 cutting a column of coal from a mine vein, of a curved chute for directing the cut column away from the unmined mass, and an extensible conveyer attached to the mining machine in fixed relation thereto and 65 movable therewith while extending the con-

veyer length in position to continuously receive the dislodged material from said chute.

6. In a mining and loading machine, the combination with mining mechanism, of 70 means for operating the same including feed thereof along a mine wall, a deflecting chute connected to said mining mechanism in position for directing dislodged material from the mine wall, an upright pivotal connection 75 between said chute and that side of said mining mechanism remote from the mine wall, and a detachable connection between said chute and said mining mechanism to permit the chute to be swung horizontally 80 on said upright pivotal connection to a position in folded relation to the mining mechanism to shorten the length of the mining and loading machine for adjustment of the mining mechanism in a narrow space 85 for the initial cutting position of the mining mechanism.

7. In a mining and loading machine, the combination with mining mechanism for cutting superposed columns of coal along a 90 mine wall, of means connected to said mining machine to move bodily therewith for directing the upper column of coal away from the mine wall and to the level of the lower column of coal, while leaving the 95 lower column of coal extending along the mine wall, and means for automatically receiving both columns of coal in parallel and conveying the same toward loading position.

8. In a mining and loading machine, the combination with mining mechanism for cutting two superposed columns of coal along a mine wall, two extensible conveyors connected to the mining mechanism, one extending along the mine wall adjacent 105 thereto and the other extending along the mine wall spaced therefrom, and means for directing the coal from one of said columns to the extensible conveyor spaced from the mine wall so that said conveyors will 110 respectively receive the cut columns of coal.

9. In a mining and loading machine, the combination with mining mechanism for cutting superposed columns of coal along a 115 mine wall, of means connected to said mining mechanism for directing one of said columns of coal away from the mine wall and to the same level as the other column of coal to arrange said columns of coal in parallelism horizontally, and means for receiving the horizontal parallel columns of coal and transferring the same toward loading position.

10. In mining and loading apparatus, the combination with mining mechanism for 125 dislodging material along the working face of a mine vein, of a belt conveyer adapted to lie flat on the floor in position to receive the dislodged material, means for directing the dislodged material from said mining 130

mechanism onto said belt conveyer, and mechanism for operating said belt conveyer by sliding the same over the mine floor.

11. In mining and loading apparatus, the combination with mining mechanism for dislodging the mineral from the working face, of an extensible conveyer comprising a belt adapted to lie flat on the mine floor in position to receive the dislodged mineral, 5 means for directing the dislodged mineral from said mining mechanism onto said conveyer, and means for operating said conveyer into various extended positions.

12. In mining and loading apparatus, the combination with mining mechanism, of an extensible conveyer comprising a belt adapted to slide over the mine floor from a predetermined loading position to the various positions taken by the mining machine 10 in its progress along the mine wall, means for directing dislodged material from the mining mechanism to said belt, and means for operating said conveyer by advancing said belt to the mining mechanism for a 20 load and retracting said belt to transfer the load to a loading position.

13. A method of mining consisting in driving spaced-apart entries along the sides of a wide pillar, dislodging the coal by 15 simultaneously operating mining machines at the rear end of the pillar while moving the same toward each other, driving an additional intermediate entry along the central portion of the pillar, loading the dislodged 25 coal onto transportation mechanism on mine tracks in the first-named entries, and using the first-named entries in circuit with the central entry to ventilate the places in the mine where the mining and loading operations 30 are proceeding.

14. In a mining machine, the combination with a plane kerf-cutter, of means for supporting the same in position to cut a plane kerf in a mine vein, and mechanism comprising a plurality of motors connected at spaced-apart positions to an annular driving gear for driving said plane kerf-cutter.

15. In a mining machine, the combination with a supporting frame, of a kerf-cutter comprising a cutter-ring, inter-locking connections between said cutter-ring and said frame, and radially arranged releasable tapered means for effecting circumferential expansion of the cutter-ring to operate said 55 interlocking connections to secure the cutter-ring to said frame.

16. In a mining machine, the combination with a supporting frame, of a cutter-ring, interlocking connections operable circumferentially between said cutter-ring and said frame, and radially arranged tapered keys for operating said interlocking connections circumferentially to secure the cutter-ring to said frame.

17. In a mining machine, the combination

with a sectional cutter-ring, of a supporting frame, interlocking connections between the sections of said cutter-ring and said frame, and radially arranged devices for operating said interlocking connections by moving said sections circumferentially on said frame to secure said sections to said frame or to permit release of said sections from said frame.

18. In a mining and loading machine, the combination with dislodging mechanism, of a belt conveyer having a receiving position continuously adjacent said dislodging mechanism, means for reciprocating said conveyer to move the dislodged material to a distant loading position and return the dislodging mechanism for another load, and means for operating the dislodging mechanism including the feed thereof along the mine wall while at the same time moving the conveyer along with the mining machine.

19. In a mining and loading machine, the combination with mechanism for dislodging coal from the working face of a mine vein progressively away from a predetermined loading position, of a reciprocating belt conveyer connected between the loading position and the dislodging mechanism at the working face where the coal is being dislodged, to effect the transfer of the coal to said predetermined loading position from various distances therefrom, and means for operating said dislodging mechanism including movement thereof away from said predetermined loading position and the corresponding extension of the conveyer.

20. In a mining machine, the combination of a kerf-cutter, comprising a supporting frame and a sectional outer ring, and radial cam devices for locking said sectional ring to said frame.

21. In a mining machine, the combination with an upright kerf-cutter, of a flat supporting plate mounted at right angles to the plane of said kerf-cutter, and means comprising spaced-apart shafts extending through said plate for driving said kerf-cutter.

22. In mining and loading apparatus, the combination with a supporting frame, of mining mechanism thereon for cutting superposed columns of coal and foreign material, said columns being for dislodgment of the coal and foreign material in large blocks, loading apparatus for separately receiving and transferring from the mine wall the large blocks of coal dislodged, and a plow connected to said frame in advance of the mining mechanism to move bodily therewith in position to transfer from the mine wall the previously dislodged blocks of foreign material.

23. In mining and loading apparatus, the combination with mining mechanism for cutting superposed columns of coal and foreign material, mechanism for directing

- one of the columns away from the mine wall and leaving the other column adjacent thereto, a plow connected to the mining mechanism to move bodily therewith in position to move previously-dislodged foreign material away from the unmined mass, and a conveyor for receiving and transferring toward loading position the foreign material separately from the loading of the coal.
- 10 24. The method of mining which consists in driving spaced-apart entries along the sides of a wide pillar, driving an additional intermediate entry along the central portion of the pillar, dislodging the coal by operations from the side entries toward the intermediate entry, loading the dislodged coal by transferring the same from the places of dislodgment along the working face toward said side entries, and providing
- 15 a ventilating system having the side entries in circuit with the intermediate entry introducing the fresh air along the side entries to effect removal of the dust-laden air from the working faces toward and along the intermediate entry.
- 20 25. In mining apparatus, the combination with a supporting frame, of means comprising a downwardly and rearwardly inclined chute mounted on said frame with its upper end in receiving position near the roof of the mine chamber, and a pick machine on said frame separately from said chute but in position to strip a layer of coal at the roof of the mine chamber from a stratum of foreign material so that the dislodged coal will fall into the upper receiving end of said chute.
- 25 26. In mining apparatus, the combination with frame-work for supporting mining machines initially in an entry at various elevations, means for operating said mining machines along terraces, and a plurality of inclined chutes for individually directing the dislodged material to a pre-determined loading position.
- 30 27. In mining and loading apparatus adapted to operate in terraced formation, the combination with a supporting frame for initially supporting the mining and loading machine spaced-apart horizontally at various elevations, and a plurality of chutes each having pivoted extensions for directing dislodged material from the various terraces to a pre-determined loading position.
- 35 28. In mining and loading apparatus, the combination with a mining machine, of a pair of belts spaced apart vertically, an additional pair of belts spaced apart horizontally, means for operating said belts for moving up grade the coal dislodged by said mining machine, and means for receiving the coal from said belts.
- 40 29. In mining and loading apparatus, the combination with a supporting frame, of mining mechanism thereon, and loading ap-

paratus comprising a reel on said frame, and a carrying belt connected to and wound on said reel and adapted to afford a conveyor extended from said mining mechanism to varying distances.

70 30. In mining and loading apparatus, the combination with a supporting frame, of mining mechanism mounted thereon, means for operating said mining mechanism including the feed thereof along a mine wall, a conveyor belt adapted to receive material dislodged by said mining mechanism, and a reel for receiving said belt and for paying it out as said mining mechanism is fed along the mine wall.

75 31. In a mining and loading machine, the combination with a supporting frame, of mining mechanism mounted thereon, a conveyor belt adapted to receive material dislodged by said mining mechanism and connected to said supporting frame, a reel for receiving and paying out the said belt, said reel being adapted to be located at a distance from said frame, and means for operating said mining mechanism along a mine vein while said belt remains connected between said reel and said frame and is being paid out from said reel.

80 32. In a mining and loading machine, the combination with a supporting frame, of mining mechanism mounted thereon, a conveyor belt adapted to rest on and slide over the mine floor, a reel on said frame for receiving and paying out said belt, and means on said frame in position for directing dislodged material onto said belt as the mining mechanism moves along the mine wall.

85 33. In a mining and loading machine, the combination with long wall mining mechanism comprising a supporting frame and mining mechanism thereon, of a conveyor adjacent the floor level and spaced from the working face of the mine wall, and deflecting mechanism comprising a gravity chute for directing dislodged material from an elevated position at the mine wall to the said conveyor adjacent the floor level.

90 34. In a mining and loading machine, the combination with a supporting frame, of mining mechanism thereon, a reciprocating belt conveyor connected to said frame and extensible from a given loading position when said supporting frame and mining mechanism is moved along the face of the mine vein, and a deflector chute mounted on said supporting frame and movable therewith in position for directing dislodged material from an elevated position at the mine wall to said extensible reciprocating belt conveyor.

95 35. In a mining and loading machine, the combination with a supporting frame, of cutting mechanism mounted thereon and adapted to cut coal in columns along a mine wall, an upright curved deflector and chute

for receiving cut columns and directing the same away from the mine wall and out of the rear end thereof, and a conveyer belt connected to said frame and extending under the rear end of said chute along a path parallel to the path of the machine.

36. In a mining machine, the combination with a plane kerf-cutter, of a flat supporting plate mounted at right angles to the plane of said kerf-cutter, and means comprising spaced-apart shafts having axes in the plane of said plate for driving said kerf-cutter.

37. In mining apparatus, the combination with frame-work having terraced supports, of a plurality of mining machines adapted to be supported on the terraces of said framework, and means for operating said mining machines from said terraces along terraces of a coal vein adjacent said framework while the latter remains in position to receive the mining machines for movement forward to new positions for operation along said terraces.

38. In mining and loading apparatus, the combination with terraced framework, of mining and loading apparatus on said framework and comprising mining mechanism movable off the said framework along terraces in the mine vein while the said loading apparatus remains permanently mounted on said framework and is extended with said mining mechanism, and means for operating said mining and loading apparatus to deliver material from the mine vein terraces to said framework.

39. In mining and loading apparatus, the combination with a portable frame, of a mining machine adapted to be supported on said frame for movement therefrom along the face of a mine vein, loading apparatus on said frame, extensible conveyer connections between said mining machine and said loading apparatus, and means for operating said conveyer connections to deliver dislodged material from the mining machine to the loading apparatus on said frame.

40. In a mining and loading machine, the combination with mining mechanism for cutting superposed columns of material along a mine wall, of means for operating said mining mechanism including feed thereof along the mine wall, a reciprocating conveyer for receiving the material from the lower columns adjacent the working face and moving such material toward loading position, an additional conveyer spaced

from the working face, a chute for directing the material from the upper columns to said additional conveyer, and means for operating said additional conveyer to move the material of the upper columns toward loading position.

41. In mining and loading apparatus, the combination of mining mechanism for cutting superposed columns of material along a mine wall, and means for directing the material of one of said columns into horizontal parallelism with the material of the other column.

42. In a mining and loading machine, the combination with mining mechanism for cutting separately superposed columns of mineral and foreign material, of means for directing the material of one of said columns into horizontal parallelism with the other column, and mechanism for loading the mineral and foreign material separately.

43. In a mining and loading machine, the combination with mining mechanism for cutting superposed columns of material along a mine wall, of means for directing the material of one of said columns away from the mine wall and to the same level as the other column to arrange said columns in parallelism horizontally, and means for loading said horizontal parallel columns of material.

44. In a mining and loading machine, the combination with mining mechanism for cutting material in columns along a mine wall, a deflector for engaging the cut column and directing the same away from the mine wall, and an extensible conveyer belt with its receiving end connected to the delivery end of said deflector and extended in accordance with the feed of the mining mechanism along a path parallel to the path of the machine.

45. In mining and loading apparatus, the combination with a supporting frame, of mining mechanism thereon for cutting superposed columns of coal and foreign material, mechanism mounted on said frame in position to direct one of the columns away from the mine wall and leaving the other column adjacent thereto, and means mounted on said frame in position to act in advance of said mining mechanism to move the previously dislodged foreign material away from the unmoved mass.

EDMUND C. MORGAN.
